UNITED STATES PATENT OFFICE

GEORGE W. PIGGOTT, OF NEW YORK, N. Y.

DESIGN FOR CARPET.

SPECIFICATION forming part of Design No. 11,834, dated June 29, 1880.

Application filed February 12, 1880. Term of patent 3½ years.

To all whom it may concern:

Be it known that I, GEORGE W. PIGGOTT, of New York, in the county and State of New York, have invented a new and original Design for Carpet, of which the following is a specification.

This invention relates to a new and original design for carpets, oil-cloths, and similar fabrics.

10 It consists in the novel grouping and configuration of figures, hereinafter more fully described and claimed.

The accompanying photograph illustrates a face view of a carpet having my new design.

15 On the background of the carpet is a central rectangular figure, *a*, and on one side, in line with figure *a*, is a group, *A*, composed of a fence, *b*, a wall, *d*, and a fence, *e*. Above this group is a rectangular figure, *f*, partially inclosing a spray, *g*, of flowers, which falls over a border, *g'*.

Between the group *A* and figure *f* is a field, *A'*, with flowers, leaves, and vines scattered over it.

20 *B* is a group composed of a cross-shaped figure, *g²*, overlaid with flowers. *C* is a right-angled border, extending from the central figure, *a*, to the group *B*. *D* is a field in-

closed by figure *a*, border *C*, and groups *A* *B*. *E* is a group of flowers, leaves, and vines, from which sprays extend in every direction. 30

F is a rectangular border, extending up from the figure *a*, and inclosing a field, in which is the group of flowers *E* and group *E'* of chains *h'*, bars *h²*, and flowers *h³*, and from group *E* a vine, *h⁴*, extends upward over the border *F*, and a branch, *i*, from the said vine extends over the border *C* into the field *D*. 35

H is a rectangular border, between which and the figure *a* and border *F* is a field, *I*, 40 traversed by branches *j* of the floral group *E*. At the bottom of the field *I* is a group, *K*, composed of geometrical figures *l l* and flowers *m*. Between the group *K* and the border *C* is a field, *L*, traversed by branches *n* of the 45 vine *h*.

I claim—

The design for a carpet, consisting of the figure *a*, groups *A* *B* *E* *E'* *K*, figures *f*, vines *h⁴* *j*, branches *n*, borders *g'* *C* *F* *H*, fields *A'* *D* 50 *I* *L*, and intervening flowers, leaves, and vines, substantially as shown.

GEORGE W. PIGGOTT.
